ENCASED BASEBOARD HEATING SURFACE

Andrew E. Reiss, Kenmore, N. Y., assigner to The Rittling Corporation, Buffalo, N. Y.

Application August 2, 1948, Serial No. 42,085

7 Claims. (Cl. 257—133)

1

This invention relates to heating apparatus, and it has particular reference to the provision of heating surface of the type adapted to be installed around the lower part of the walls of a room—commonly called baseboard surface—and to casing and supporting means therefor.

It has heretofore been proposed to heat the rooms of buildings by means of coils or lengths of pipe extending around the walls of the room, and to provide a protective casing over the coils. The piping is supplied with steam or hot water, and this form of heating surface constitutes one alternative to the well known upright cast iron radiators. It has also been proposed to form the heating surface from one or more lengths of metallic tubing provided with heat conducting fins which extend the heat transfer surface of the tubing, and to mount the heating elements close to the floor line. An installation of this character is sometimes referred to as a baseboard heater, inasmuch as it is located at that region of the wall usually finished with a baseboard or lower portion of panelling.

While baseboard heating surface is adequate to supply sufficient heat to a room, and has certain advantages over other types of heating systems from the viewpoint of overall performance, it has not met with complete acceptance. One reason relates to the relative costs of installation, a large portion of which is chargeable to labor. Another objection is that the air circulating through the heating coils may deposit dirt on the walls, rendering the appearance of the room unsightly and necessitating frequent cleaning. Still another objection is that the casing does not blend into the architectural or decorative scheme, and it is therefore not used for esthetic reasons.

According to the present invention, these and other objections are met by providing an improved heating coil of the fin and tube type, so constructed and arranged that manufacturing and installation costs are reduced, wherein an easily applied and detachable and decorative casing is incorporated, and which will meet the requirements of a wide variety of applications in an efficient manner. The principles and advantages of the invention will be fully understood from the following description of a preferred embodiment, illustrated in the accompanying drawing, wherein:

Fig. 1 is a perspective showing the heating coil and casing installed in a corner of a room;

Fig. 2 is a transverse section drawn on an enlarged scale;

2

Fig. 3 is a perspective of a coil mounting and cover retaining bracket;

Fig. 4 is a top plan; and

Fig. 5 is a section taken substantially on the line 5—5 of Fig. 2, drawn on an enlarged scale and showing novel inlet and outlet fittings.

The heating surface comprises a coil 10 having lengths of tubing 11 and 12 which are transversely intersected and connected by a series of spaced rectangular fins 13 which are secured by soldering, brazing, or expanding the tubes after the fins have been assembled. The coil 10 may be formed in convenient lengths adapted to the installation dimensions to be encountered, and it can be assembled on the job as hereinafter more fully explained. As shown in Fig. 1, the coil is mounted at and against the lower portion of one or more of the walls 14, 15, of a room, being elevated from the floor 16 approximately one and one-half inches. The fins 13 may be approximately two by five and one-half inches, from which it will be apparent that the coil may be installed at the baseboard region of the room to have generally the same overall height and to project only slightly farther over the floor area.

The coil 10 is supported along the wall and above the floor by means of a series of mounting brackets 21, shown in perspective in Fig. 3. These brackets are angle shaped, having a wall flange 22 formed with apertures 23, and a coil flange 24 formed with pipe notches 25 and 26. The notch 25 is U-shaped, and is cut from the top margin of the flange 24, while the notch 26 is cut from the side margin to underlie the notch 25. Each notch is formed with a rounded bottom of such size as to receive the tubes 11 and 12. It is to be noted that the wall flange 22 is of less height than the coil flange 24, thereby providing a clearance gap 27 above the top edge of the flange 22 and the adjoining inner edge of the flange 24. This gap has a thickness equal to or slightly greater than the thickness of the metal from which the bracket is formed. Additionally, the coil flange 24 is provided with an outwardly and downwardly extending finger 28 along its front edge and below the notch 26, and the finger terminates in a rounded toe portion 29 projecting below the lower edges of the flanges.

In order to mount the coil 10, the brackets 21 are secured against the plaster (the baseboard itself preferably having been removed or omitted) by means of screws 31, as best shown in Figs. 2 and 5. A tight connection can readily be obtained by spacing the brackets 21 to about the wall adjacent every other stud, so that the screws

can seat in the woodwork, rather than in the plaster alone. A coil section is then lifted up over the brackets, the flanges 24 passing between adjacent fins 13, and the tube 11 passing over the upper edges of the flanges. It will be noted that the flange opening 26 is longer than the flange opening 25, so that the lower tube 12 may enter its notch without interference while the tube 11 is elevated above the top of the bracket. When the tubes are aligned with the notches, the coil may be dropped into place, and it obviously will be securely held except against intentional dismantling.

It is further to be noted that the flanges 24 have substantially the same width and height as the fins 13. The edges of the fins and the flanges 24 will therefore be in substantially the same planes when the coil section is located, only the finger 28 projecting beyond the coil. Due to the direct metallic contact between the tubes and brackets, the latter therefore add to the indirect heating surface and accordingly to the total heat transfer capacity.

As best shown in Fig. 5, the projecting ends of the tubes 11 and 12 are connected to manifold inlet and outlet fittings 33 and 35 respectively. In some installations, as will be readily understood by those skilled in the art, it may be desirable to connect two or more sections 10 directly to each other before connecting the ends to the fittings. In Fig. 5, it has been assumed that the left hand end is the inlet end for whatever over-all length of coil 10 has been installed, while the right hand end is the discharge end. Heating fluid, such as steam or hot water, is supplied through a riser 32 for distribution to and through the coil, while condensate is returned to the boiler through a return line 34.

The inlet manifold 33 comprises a relatively short length of tubing having angularly disposed portions 36 and 37, the section 37 having an overall length approximating the height of the coil 10, and being formed with two nipples 38 and 39 which can be abutted against or telescoped over the tubes 11 and 12, and thereafter made fluid tight by brazing. The upper end of the leg 37 is also formed with a reduced neck 41 which is tapped, and is adapted to receive either a plug 42, or a standard air bleed valve, not shown. The nipples 38 and 39 are equally spaced from the extremities of the leg section 37, and they are also aligned in the vertical plane, so that the fitting 33 can be turned upside down, and still engage the tubes 11 and 12. Under this condition, the lower trace of the fitting would be in the same horizontal plane as the upper end of the reduced portion 41, while the end of the portion 41 would then be in substantially the same horizontal plane as the lower edges of the fins 13 and brackets 21.

This construction permits the steam fitter to couple the coil into the supply line with either bottom or overhead feed, as he may elect to do depending on the nature of the system and location of supply line, but without disturbing the relations desired between the coils and the baseboard location.

The outlet fitting 35 is formed to embody the same features of universality, and also to make additional provision for an air trap. The fitting comprises angularly related sections 44 and 45, and the vertical section 45 merges into a receiver 46 formed with a tapped vent 47. Tube nipples 48 and 49, adapted to be connected to the

tubes 11 and 12, extend respectively from the section 45 and the end of the receiver 46, with the centers in the same vertical plane and their ends also aligned. The over-all height of the fitting, and the location of the nipples 48 and 49 with respect thereto, again are such that the fitting can be inverted and still line up with the coil tubes and brackets.

The receiver 46 is shown as equipped with a conventional air vent valve 51 instead of a plug, so that air trapped in the coil length can collect in the overhead space of the receiver without serious interference with the flow of heating fluid. The valve 51 may be opened as occasion requires to purge the air. When the fitting is inverted, the opening 47 may be plugged or provided with a drain valve.

The coil assembly is enclosed by a sheet metal casing generally comprising a top cover and deflector section 53, a front cover section 54, and a bottom damper section 55. As best shown in Fig. 2, the top cover section 53 is formed with an imperforate back plate having a depending flange 57, an angularly bent overhanging flange 58, and a reversely bent flange 59 disposed at a right angle to the flange 57. The flange 57 is connected by spot welding or other suitable means to a vertical flange 61 of the top cover proper, and the flange 61 is continuous with a right angled perforated flange 62. The thickness of the combined flanges 57 and 61 is equal to or slightly less than the thickness of the flange 22 of the bracket 21, so that the cover section 53 can be slipped into the clearance gap 27, and thereby secured in position. When the flanges 57 and 61 are seated, the perforated flange 62 contacts the upper edges of the fins 13 and the brackets 21.

As best shown in Fig. 4, the perforations in the flange 62 are made as a series of elongated slots 63, whose combined area represents a high percentage, say seventy-five per cent, of the total area of the flange 62. Inasmuch as the cover flange rests on the edges of the fins and brackets, adequate support and resistance to bending is provided. It is intended that the connecting portions between the slots 63 may be cut out as required, so that valves, such as the valve 51, may be readily accessible. As shown in Fig. 5, for example, the cover 62 rests not only on the edges of the fins, but also barely contacts the receiver 46, while the valve 51 projects above and in front of the deflector flange 58. The top cover and deflector section may be retained in position after assembly by means of a moulding strip 65 nailed over the flange 59, and which also adds to the decorative finish and simulation of a conventional baseboard.

The front edge of the cover section 62 is also formed with a reversely bent upstanding flange 66 which provides a tongue for the reception and retention of the front cover 54. The front cover is preferably imperforate, and it comprises a sheet of sufficient width to abut the front edges of the fins and brackets, and an upper reversely bent hooked portion 67 which fits over the flange 66. The lower portion of the cover 54 is bent outwardly to follow the contour of the fingers 28, and the lower edge 68 is bent inwardly to hook under the toe elements 29 of the brackets 21. In assembly, the hooked edge 67 is seated on the flange 66, and the cover is then struck sharply along the bottom edge, to snap the edge 68 under the toes 29. This connection retains the front cover in position against all adventitious strains,

but it permits the front cover to be removed for cleaning purposes by simply tugging at the inner turned lower edge.

The bottom damper section 55 comprises a back plate 71 whose upper edge is rolled to form a hinge joint with a similarly rolled plate 72. The plate 72 is preferably slightly curved, as shown in Fig. 2, and it is of such width that, when elevated against the bottom of the coil 10, its forward edge closely approaches the inner edge of the cover 54. When the plate 72 is down in the full line position shown in the figure, flow of air through the coil and out through the top cover takes place as shown by the arrows. It will be seen that the angular inclination of the plate 72 provides a scoop to direct the air into the casing, just as the deflector flange 58 serves to direct the warm air outwardly.

When the damper 72 is elevated, air flow is substantially stopped, and therefore only a small amount of heat will be supplied from that section of the coil. The damper plates 72 may be made in lengths which can be conveniently handled along the length of the wall, and independently operated by any suitable means. There is herein illustrated a pull chain 73 extending up through the coil 10, and adapted to be caught in a small slot cut into the top cover 62 at any convenient point. By dividing the damper plate 72 into a number of sections, heating may be uniformly distributed around the wall or localized, as conditions may demand. The damper section may be retained in position by a moulding strip 14 nailed to the wall and the floor.

To install the surface and casing, the recommended procedure is to remove the baseboard, if there is one in the room, and then secure the lower damper section 55 in position. Nailing is not only facilitated, but the upper edge of the back plate 71 may be utilized as a gauge for the lower edges of the brackets 21, which are next located. The coil 10 is then placed in position and the necessary steamfitting connections are made. Then the deflector plate and top cover assembly 53 are positioned and secured, and all that remains to be done is to apply the removable front cover.

The deflector section 58 serves to divert the emergent air stream away from the walls and out into the open space, thus minimizing the formation of smudge marks. It has also been found that the curved damper plates tend to prevent the accumulation of dirt along the moulding 14, and that the clearance gap beneath the coil, when the dampers are closed, is sufficient to give this space a thorough cleaning with a vacuum cleaner of any conventional household type. Dust collecting on the coil 10 may be periodically removed by taking off the front cover and applying either cleaning nozzle or dust brush.

It will also be seen that the casing provides an attractive appearance, and that it may be finished to blend with practically all standard architectural designs and interior finishes. The coil may likewise be installed with a minimum of labor, and it is coordinated with the casing members to provide an efficient heating assembly.

While the invention has been particularly described with reference to a preferred embodiment thereof, it is to be understood that it is susceptible of numerous modifications and variations without departure from its principles, and it is therefore intended to include all constructions which fall within the scope of the following claims.

I claim:

1. Baseboard heating surface comprising a length of tubing having transverse spaced fins affixed thereto, bracket members for securing said tubing along a wall, said bracket members having a flanged portion of substantially the same width and height as the fins and a thickness less than the distance between adjacent fins, said flanged portion being formed with a notch along an edge thereof in which the tube is supported, the depth of the notch being such that the edges of the fins and flanges lie substantially in a common plane, a perforated top cover member positioned over the upper edges of the fins and flanges, and a front cover member positioned over the front edges of the fins and flanges and being detachably connected to said flanges.
2. Baseboard heating surface comprising parallel lengths of tubing having spaced transverse fins affixed thereto, bracket members for securing said tubing along a wall, said bracket members having a wall flange and an angularly related coil flange, the coil flange having a width and height substantially equal to the width and height of the fins, notches cut into the coil flange along adjacent edges thereof, said notches being of such depth and width as to receive the tubes and locate the fins in aligned relationship with the flanges, inlet and outlet fittings at the ends of the tubes and connected thereto to couple the tubes in parallel, said fittings having an overall height substantially coextensive with the height of the fins and being aligned at top and bottom with the edges of the fins, and cover members positioned over and along the top and front edges of the fins and brackets.
3. Baseboard heating surface comprising parallel lengths of spaced tubing, spaced transverse fins intersecting the tubing and affixed thereto, the fins extending above and below the tubing equidistantly and also equidistantly to each side thereof, bracket members for mounting the tubing along a wall, said bracket members each comprising a wall flange and an angularly related coil flange, said coil flanges having substantially the same width and height as the fins, notches cut in the top and side edges of the coil flanges along the longitudinal center line thereof, the notch along the top edge being of such depth that when a tube length is supported therein the upper edge of the fins are aligned with the top edges of the coil flange, the notch along the side edge being of greater length than the notch in the top edge and being adapted simultaneously to support another length of tubing, whereby the tube and fin assembly may be pushed over the brackets and toward said notches and dropped into retained position, a clearance gap formed at the rear of the coil flanges, a top cover adapted to rest on top of the fins and brackets and having an angular section adapted to engage in the clearance gap, and a front cover section adapted to be connected to the top cover and abut the forward edges of the fins and coil flanges.
4. Baseboard heating surface comprising a heating coil adapted to be mounted along the baseboard region of a room wall, mounting brackets for supporting the coil along the wall, said brackets comprising angularly related wall flanges and coil flanges, the coil flanges being formed with notches for engaging and supporting the tubes of the coil, a clearance gap formed at the rear edge of the coil flanges, an outwardly and downwardly projecting finger formed at the forward edges of the coil flanges, a top cover sec-

tion having a flange portion adapted to seat in the clearance gap, an outwardly and upwardly extending deflector flange and a horizontally extending top cover flange, said last named flange being perforated and resting on the tops of the bracket coil flanges and being formed at its forward edge with a reversely bent tongue, a front cover plate having a hooked flange adapted to engage over said tongue and an inturned lower margin adapted to hook under said fingers.

5. Heating surface adapted to be disposed along the lower portion of the walls of a room comprising a heating coil having parallel tubes and extended fins connected thereto, fittings at the ends of the coil and disposed within the area delimited by the fins, mounting brackets for the coil comprising angularly disposed wall and coil flanges, said coil flanges being formed with notches to receive and support the tubes of the coil, said brackets being formed with clearance notches on the wall side thereof and a projecting finger on the room side thereof, a front cover having a reversely bent margin adapted to hook over the finger, top and bottom covers for the coil adapted to extend into the room substantially the width of the brackets, at least one of said last named covers having a flange portion seated in said clearance notches and at least one of said last named covers being hingedly mounted for movement toward and away from the adjacent ends of the brackets, said hingedly mounted cover when positioned against the brackets providing a damper to interrupt the flow of air and when swung away from the brackets providing an air directing means.

6. Baseboard heating surface comprising a heating coil having parallel lengths of tubing adapted to be mounted along the lower portion of a room wall, heat radiating fins connected to and extending from the tubing, inlet and outlet fittings connected to the tubes at the ends thereof, each of said fittings having a vertical leg portion and nipples extending therefrom for connecting the tubes in parallel, the over-all height of the fittings and the location of the nipples being such that the fittings may be assembled with either end thereof in top or bottom position with respect to the coil and the extremities of the fittings lying within the area delimited by the coil, mounting brackets for the coil comprising angularly related wall and coil flanges, said coil flanges having a height and width substantially coextensive with the height and width of the

coil, a clearance notch formed between the wall and coil flanges to space a portion of the coil flange from the wall, a cover member having an outwardly extending flange adapted to overlie the edges of the brackets along one end thereof and an angularly disposed flange adapted to seat in the clearance notches, a deflector flange connected to the cover flange adjacent said angularly disposed flange and projecting upwardly and outwardly therefrom, a damper plate pivotally mounted at the opposite end of the coil beneath said coil flanges, and a front cover positioned over the room face of the coil and bracket edges, said front cover having marginal portions interengaged with said first named cover and said brackets.

7. A casing member for a baseboard tubular heating coil comprising brackets having angularly related wall flanges and coil and casing flanges, said coil flange being formed with notches to support the tubing of the coil, a portion of the wall flange being cut away at its junction with the coil flange to provide a clearance gap at the rear edge of the coil flange, an outwardly and downwardly projecting finger on the front edge of the coil flange and diagonally opposed to the clearance gap, a top cover and deflector member having a wall flange adapted to seat in the clearance gap, an outwardly and upwardly deflecting flange, and a top cover flange disposed at right angles to the wall flange, said last named flange being formed with perforations and having a forward upwardly turned tongue adapted to overlie the forward portion of the coil flange, and a front cover plate formed with a reversely bent hook along one edge adapted to engage over said tongue and an inwardly rolled margin along the opposite edge adapted to engage under said fingers.
